UNITED STATES PATENT OFFICE.

HARRY MITCHELL, OF NEEPAWA, CANADA.

SAWBUCK.

SPECIFICATION forming part of Letters Patent No. 628,015, dated July 4, 1899.

Application filed November 22, 1898. Serial No. 697,173. (No model.)

To all whom it may concern:

Be it known that I, HARRY MITCHELL, a subject of the Queen of Great Britain, residing at Neepawa, Manitoba, Canada, have invented 5 certain new and useful Improvements in Saw-bucks; and I do hereby declare the following to be a full, clear, and exact description of the invention, such as will enable others skilled in the art to which it appertains to make and to use the same.

The invention relates to sawbucks, and more particularly to that class which are adapted to be folded into compact shape for transportation.

15 The objects of the invention are to do away with the necessity of putting the knee or the foot upon the stick or log to be held while sawing the same and to provide simple and effective means for holding the stick to be 20 operated upon in such manner as to leave the operator in the best position for operating the saw.

It consists in the combination, with the buck, of spring clamping-jaws connected with 25 a foot-lever or treadle and operating through a slotted guide connected with the cross-bar connecting the legs of the sawbuck and in certain details of construction and arrangement 30 of the parts of the sawbuck, as will be hereinafter particularly described and claimed.

In the accompanying drawings, Figure 1 represents a perspective view of the improved sawbuck in operative position. Fig. 2 is a 35 front elevation of the same closed for transportation. Fig. 3 represents a transverse vertical section showing the parts in position for operation. Fig. 4 is an enlarged detail perspective view of the slotted spring-jaw guide-plate; and Fig. 5 is an enlarged detail 40 perspective view of the upper end of one of the legs, showing the saw-holding clip applied thereto.

11 and 22 indicate the legs of the sawbuck, connected by a cross-bar 3, the construction 45 and arrangement of these parts, except in certain details hereinafter described, being similar to such as are in common use. The outer legs 11 are perforated to receive the rounded ends of the cross-bar 3, which are 50 firmly secured in said legs, being keyed or otherwise rigidly secured therein. The legs 22 are pivoted upon the cross-bar 3 to swing

freely thereon inside of the legs 11, which are recessed on their inner faces at *a* and have pivoted to them links or rods 4, which 55 at their opposite ends pass through eyes or staples 5 on the legs 2 and have hooks 4', which engage said eyes for holding the buck in operative position. In folding the buck the links slide through the eyes and fold down 60 snugly in the recesses *a*. Upon the cross-bar 3, at or near the center of its length, is rigidly secured a transverse plate 6, provided with a slot 7, extending across and beyond the bar 3, and within said slot, upon the opposite sides 65 of the bar 3, are arranged the clamping-arms 8 8, formed from a single piece of spring-steel in loop or V shape, preferably brought into close proximity below the bar 3, as indicated at 70 9, from which point they are bent into the form of a pendent loop or eye 10. The arms above the point 9 diverge thence to their upper ends, which are bent inward toward each other and preferably slightly downward for adapting 75 them to engage the stick being operated upon. The loop portion 10 of the spring is preferably expanded in width or hammered out and made thinner for giving it the desired elasticity and adapting the diverging hook ends of the arms 8 as they are carried downward through the 80 slot 7 to be made to approach each other for grasping the stick or log between them, the angle of divergence of the arms being such as to cause the arms to automatically rise under the tension of the spring for releasing the log 85 when the spring-arms are released for that purpose. The loop or eye 10 has extending through it a suitable strap or cord 12, the ends of which are connected to eyes 13 13 on opposite sides of a foot-lever or treadle 14, which 90 at its lower end is connected by suitable eyes with a cross bar or rod 15, connecting the lower ends of the inner legs 22. Also secured within the loop 10 is a pendent loop or link 16, adapted when the buck is to be folded for 95 transportation to engage the hook 17, secured to the treadle 14. By this arrangement the treadle is adapted to swing freely upon the rod 15 under the action or pressure of the operator's foot thereon. The hook 17 is preferably arranged in a depression or cut-off portion in the treadle, as indicated at 18, in such manner that it is brought flush with or below the surface of the treadle, thereby preventing 100

its catching the foot of the operator. The legs 1 1 are provided intermediate the cross-bar 3 and the links 5 with wedge-shaped tapering blocks 19, which serve when the legs 2 2 5 are folded within the legs 1 1 to hold them securely in their folded position. In lieu of the wedges 19 round-headed brass nails or tacks 19^a may be driven into the legs 1 and made to frictionally engage the legs 2 when to the sawbuck is folded.

20 indicates an angular clip secured to the right-hand leg 2, near its upper end, and adapted to receive and hold the blade of the saw, with the lower or heel end of the saw-frame 15 resting upon the ground when not in use. This clip is rigidly secured to the leg 2, and its inner portion, lying parallel with the inner face of the leg, is sufficiently removed therefrom to receive the saw-blade and hold the 20 same in a vertical position.

By the construction shown and described when a log is placed in position upon the sawbuck the operator places one foot upon the treadle 14 and pressing downward thereon 25 draws the spring clamping-arms 8 8 downward through the slotted plate 6, thereby forcing the arms inward toward each other and causing them to grasp and through their hooks 11 to firmly hold the log in position during the 30 operation of sawing the same. Upon removing the pressure of the foot from the treadle owing to the outward tension of the arms they are immediately caused to spring upward and outward, thereby releasing the stick or log, 35 which can then be readily removed or moved endwise into position for again operating thereon in the manner described.

In folding the sawbuck for transportation the loop 16 is drawn downward and made to 40 engage with the hook 17 on the treadle, thereby drawing the upper ends of the clamping-arms 8 8 into the desired close relation to each other; and the links 4 will slide through the eyes 5 and swing down, permitting the 45 legs to be folded, the one pair within the other, in the position indicated in Fig. 2.

In sawing with the buck described it will be apparent that the legs and back of the operator will be in an upright position and the 50 weight of the body almost directly over the work, which saves the back from strain and the knee and pants from being injured, be-

sides giving to the operator a much easier and more natural position.

It will be apparent that the form of the 55 treadle or foot-lever and of the other parts of the sawbuck may be varied from those shown and described without departing from the spirit of this invention.

Having thus described the invention, what 60 is claimed as new, and desired to be secured by Letters Patent, is—

1. In a sawbuck, the combination with the cross-bar thereof, of the oppositely-disposed sliding spring-jaws, the pivoted foot-lever or 65 treadle for operating the same, a suitable connection between said sliding jaws and foot-lever, and means for forcing said jaws toward each other as they are drawn downward, substantially as described. 70

2. In a sawbuck, the combination with the cross-bar thereof, of the folding legs, the slotted plate on said cross-bar, the sliding clamping-arms moving in said slotted plate, and the foot-lever or treadle connected to said clamping-arms for operating them, substantially as 75 described.

3. In a sawbuck, the combination with the folding legs thereof, of the cross-bar, the slotted plate secured to said cross-bar, the spring 80 clamping-arms operating through said slotted plate, and a foot-lever or treadle connected to said clamping-arms for depressing said arms, said arms being adapted to be retracted for releasing the log by their spring tension 85 when the weight on the treadle is removed, substantially as described.

4. In a folding sawbuck, the cross-bar thereof provided with a slotted transverse plate, the spring clamping-arms moving within the 90 slots in said plate, the foot-lever to which said arms are connected for operating them, provided near its swinging end with a hook, and a link connected to the looped end of the clamping-arms for engaging said hook for 95 holding the springs compressed when the buck is folded for transportation, substantially as described.

In testimony whereof I affix my signature in presence of two witnesses.

HARRY MITCHELL.
